APPARATUS FOR CRACKING OIL

Original Filed March 28, 1921

UNITED STATES PATENT OFFICE

GUSTAV EGLOFF AND HARRY P. BENNER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA

APPARATUS FOR CRACKING OIL

Application filed March 28, 1921, Serial No. 456,221. Renewed March 18, 1929.

This invention relates to improvements in apparatus for cracking oil and refers more particularly to that type of apparatus in which the oil is fed through a heating chamber, as for example, a continuous coil located in the furnace, thence delivered in substantially liquid condition to an expansion chamber where vaporization takes place, the vapor drawn off and subjected to suitable 10 condensing action.

In apparatus of this character, the vapors are first subjected to a reflux condensing action where the heavier portions are condensed and continuously returned to the system for further treatment. The lighter or 15 completely converted hydrocarbons pass to a final condenser and thence to a receiver. It is highly desirable to get a close dephlegmation or fractionation of the vapors as they 20 leave the expansion chamber in order that the pressure distillate may as closely approximate the desired finished product as possible. It is also desirable to effect a heat interchange between the vapors and the incoming 25 raw oil to be treated, which may be accomplished by bringing the cold raw oil into contact with the hot ascending vapors.

The foregoing is accomplished in our present invention but in connection with certain 30 novel features. For example, instead of bringing the oil in a stream into contact with the vapors, it is preferably brought in the form of a spray like fog which produces a much more effective heat interchange, more effective reflux condensation as well as pre- 35 heating of the oil to be treated.

It is also understood by those skilled in the art that certain types of oil or even certain cuts or fractions of the same oil differ 40 widely in character from other oils or other cuts of the same oil. This is particularly noticeable in the extent of dephlegmation or reflux condensation to which the oil is subjected. It also may be desirable as the process 45 proceeds to vary the extent of dephlegmation either due to the fact that the dephlegmator is becoming hotter or to variations in temperature from changes in weather conditions. By means of the present invention, 50 various types of oil or various fractions of

the same oil can have the desired dephlegmation or the dephlegmator readily controlled or varied as the process proceeds and all in the same apparatus. The invention will appear more particularly from the accompanying 55 drawings, in which

Fig. 1 is a view, partly in vertical section and partly in side elevation.

Fig. 2 is an enlarged sectional view of one 60 of the nozzle members.

Referring in detail to the drawing, 1 designates the furnace provided with burner 2, stack 3 and combustion space 4. In the combustion space 4 is mounted the heating coil 5 which may take the form of a continuous length of say, 4" pipe. The inlet side of this coil is connected by feed line 6, which in turn is connected to charging line 7 leading to the feed pump 8 connected to any suitable source of raw oil supply. A throttle valve 9 is interposed in the connection between the pipes 6 and 7. The discharge side of the coil is connected by transfer line 10 having throttle valve 11 to one end of an elongated expansion chamber 12 located outside of the fire zone. This expansion chamber 12 is provided with a residue drawoff pipe 13 controlled by a throttle valve 14 and with a vapor outlet pipe 15 extending into the lower end of a vertical dephlegmator 16 and provided with a spaced cap member 17, this cap member being so arranged as to permit the vapors to pass freely into the dephlegmator but preventing the reflux condensate from falling back into the expansion chamber. Instead the reflux condensate is returned by pipe 18 having throttle valve 19 to the feed line 6. This dephlegmator is divided into a plurality of compartments 20 by means of the preferred circular baffle plates 21. 80 Means are provided for delivering the raw oil in the form of a spray or fog into any one or more of these compartments. To this end, a branch header pipe 22 having a throttle valve 23, is connected to the charging line 7 85 and is provided with a plurality of branch pipes 24, connected to the side of the dephlegmator as clearly shown in the drawings and each provided with a pair of throttle valves 25 and 26. Between each pair of 90 95 100

throttle valves is interposed a nozzle 27, the construction of which is more clearly shown in Fig. 2. Each of these nozzles is provided with flanged members 28 and 29 whereby they may be detachably secured to the corresponding flanges 30 and 31. The flange 28 is secured to a curved pipe section 32, provided with a flanged portion 33. To the flanged portion 33 is secured a short pipe section 34 by means of the screw-threaded flange 35, gasket 36, packings 37 and through bolts 38. The gasket 36 is provided with a screw-threaded centrally disposed apertured boss 39 to which is fixed as shown, the nozzle sleeve 40. The other end of this nozzle sleeve is closed by the valve-operated plugs 41 and 42 having the centrally disposed valve stem 43. The arrangement is such that the size of the apertures through which the raw oil enters the dephlegmator may be controlled. In addition, by suitably regulating the valves 25 and 26, the volume and velocity of the oil entering the dephlegmator may be varied relative to each other. For example, if the pressure on the pipe 22 is 1000 pounds, with the ability to deliver 1000 gallons of oil per hour, the volume of oil entering the dephlegmator may be reduced to 500 gallons per hour and the pressure regulated to, say, 200 pounds. It is also to be noted that oil may enter through any one or more of the branch pipes simultaneously and furthermore, that a larger volume may enter through one pipe than another at a different velocity than that going through a different pipe. The uncondensed vapors may be drawn off through any one or more of the branch pipes 44 controlled by throttle valve 45 and leading to the main header 46 which in turn connects to the upper end of the condenser coil 47 and is provided with throttle valve 48. The condenser coil 47 is connected by pipe 49 having a throttle valve 50 to the top of receiver 51. This receiver 51 has the usual pressure gauge and liquid level gauge and is also provided with the gas outlet pipe 52 controlled by throttle valve 53 and distillate drawoff pipe 54 controlled by a throttle valve, 55.

The process may be operated as follows: At the beginning of the run, the valve 23 may be closed and the valve 9 opened. The oil, as for example, Kansas fuel oil may be heated to a temperature in the transfer line of say, 820 degrees F. and delivered in substantially liquid phase to the expansion chamber where vaporization takes place. As the vapors begin to pass into the dephlegmator, the valve 9 may be closed, the valve 23 opened. All of the raw oil may then be passed through the uppermost pipe 24 or through any one or more of the pipes. As the run proceeds, any one or more of the pipes may be cut out. This may be varied in connection with the kind of oil treated, the end point of the

product desired in the receiver as well as weather conditions which may affect the temperature of the dephlegmator. The reflux condensate mixed with the raw oil is continuously delivered to the heating coil for further treatment. The vapors may be drawn off through any one or more of the pipes 44. The whole system may be maintained under a pressure of say, 140 pounds to the square inch but it is to be noted that by suitably regulating the valves 25 and 26, the velocity and volume of the oil entering the dephlegmator may be controlled or varied and in addition, the oil may enter in the form of a very fine mist or fog.

We claim as our invention:

1. In an apparatus for treating hydrocarbon oil, a heating coil located in a furnace, an expansion chamber located outside the furnace, a dephlegmator in communication with said expansion chamber, means for initially supplying raw oil to said coil, means for diverting the supply of raw oil from said coil and means for passing said diverted raw oil through a plurality of independent streams into separate portions of said dephlegmator, means for controlling the volume and velocity of the oil being introduced through each of said streams, means for taking off uncondensed vapors from said dephlegmator and means for condensing and collecting the said vapors.

2. In an apparatus for treating hydrocarbon oil a heating coil located in a furnace, an expansion chamber located outside the furnace, a dephlegmator in communication with said expansion chamber, means for initially supplying raw oil to said coil, means for diverting the supply of raw oil from said coil to the dephlegmator, means for introducing the diverted raw oil into the dephlegmator in a plurality of independent streams, means for independently controlling the volume and velocity of the oil being introduced through each of said streams, means for returning reflux condensate and raw oil from said dephlegmator to said coil, means for taking off vapors from separate portions of said dephlegmator to be condensed and the resulting distillate collected, means for withdrawing heavy residuum from said expansion chamber and means for maintaining a regulated pressure on the oil undergoing conversion.

GUSTAV EGLOFF.
HARRY P. BENNER.
